US00D521456S

(12) **United States Design Patent** (10) **Patent No.:** **US D521,456 S**
(45) **Date of Patent:** **** May 23, 2006**

(54) **FEMALE PLUG CONFIGURATION**

(75) Inventor: **Shawn J. Kondas**, Kendallville, IN
(US)

(73) Assignee: **Pent Technologies, Inc.**, Kendallville,
IN (US)

(**) Term: **14 Years**

(21) Appl. No.: **29/217,829**

(22) Filed: **Nov. 16, 2004**

(51) **LOC (8) Cl.** **13-03**

(52) **U.S. Cl.** **D13/154; D13/147**

(58) **Field of Classification Search** **D13/146,
D13/147, 156, 173; 439/79, 108, 367, 588,
439/606-610, 637-638, 660**

See application file for complete search history.
